DESIGN.

—
J. L. FOLSOM.

CARPET.

No. 18,152.

Patented Mar. 6, 1888.

UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 18,152, dated March 6, 1888.

Application filed January 26, 1888. Serial No. 262,078. Term of patent 3½ years.

To all whom it may concern:

Be it known that I, JAMES L. FOLSOM, of Brooklyn, in the county of Kings and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face view 15 of a carpet showing my new design.

My design consists of several clusters of leaf and flower forms, the different clusters being connected by large scrolls having somewhat

the appearance of leaves. The clusters are composed of a principal flower form and one 20 or more smaller flower forms, combined with a number of leaves, some of which are deeply serrated, while others have rough irregular outlines. Projecting from and connecting these clusters of flower and leaf forms are the 25 long leaf-shaped scrolls, from which project small twigs or stems bearing small leaves.

What I claim as new, and desire to secure by Letters Patent, is—

The design for carpets, consisting of the de- 30 sign substantially as shown.

JAS. L. FOLSOM.
